UNITED STATES PATENT OFFICE.

JAMES LOSE, OF BORDENTOWN, NEW JERSEY.

WINDOW BOX.

Application filed September 16, 1926. Serial No. 135,833.

The invention relates to improvements in window boxes, used primarily for keeping food stuffs at a low temperature, and it is the object of such invention to provide a device of this class which will be exceptionally simple and inexpensive, may be easily manufactured and sold at small cost, and will be highly efficient and desirable, provision being made whereby the device is effectively held in place within a window frame, when the lower sash of the window is partially raised.

With the foregoing in view, the invention resides in the novel subject matter herein-after described and claimed, the description being supplemented by the accompanying drawings.

Figure 1 is an inner side elevation showing the application of the invention to a window.

Figure 2 is a horizontal sectional view on line 2—2 of Figure 1.

Figure 3 is a vertical sectional view on the plane of line 3—3 of Figure 1.

Figure 4 is a perspective view of the invention disconnected from the window.

In the drawing above briefly described, illustrating the preferred form of construction, F designates a vertically disposed rectangular frame, said frame having a lower side bar 5 adapted to rest upon the sill S of a window frame, an upper side bar 6 constituting an elevated sill to support the lower sash L of the window, and a pair of vertical end bars 7 for reception between the usual sash guides G. A narrow strip 8 is preferably secured to the inner side of the upper bar 6 to lie against the lower rail of the sash L preventing rain from beating in at this point.

The single frame F supports both a box B and a door D for giving access to said box. The door D and the box B are preferably formed from wire-reinforced glass held by wood or metal frames, metal being preferably employed for these frames, whereas the frame F will in most instances be constructed from wood.

The box B comprises a top 9, a bottom 10, two parallel side walls 11, and an outer end wall 12, the inner end of said box being open and being snugly embraced or surrounded by the frame F. At suitable location, this box is provided with rigidly secured attaching plates 13 which project inwardly beyond

its open end and are secured to the inner edge of the frame F, by screws or the like 14.

The door D is preferably formed of two sections as shown, and said door is receivable within the frame F, the sections being connected to this frame by hinges 15, so that the door may be inwardly opened whenever access must be had to the box B. Any desired latch 16 may be employed for normally holding the door in closed position, in which position, the door sections abut stop beads 17 which are formed integrally with the inner edge of the frame F.

It will be seen from the foregoing that the invention is of simple and inexpensive nature and may therefore be manufactured and marketed at minimum cost. Moreover, the device may be easily applied to or disconnected from a window and when it is in use, will be highly efficient and desirable for the purposes intended.

I claim:—

1. In a device of the class described, a rectangular box for disposition at the outer side of a window, said box having an open inner end and being provided at said end with projecting attaching plates, a rectangular vertically disposed frame snugly embracing said inner end of said box, fasteners securing said attaching plates to the inner edge of said frame, and a door hinged to said frame, the latter being adapted for reception between a window sill and an elevated lower sash, the vertical end members of said frame being receivable between the usual guides for said sash.

2. A device of the class described comprising a rectangular frame composed of a lower side bar to rest on the sill of a window frame, an upper side bar constituting an elevated sill to support the lower window sash in raised position, and two vertical bars secured to said side bars and adapted for snug reception between the usual guides of said lower sash, a box having an inner open end removably inserted in the outer portion of said frame, means for removably securing said inner end of the box in said frame, and a door at the inner side of said frame to close the inner open end of the box.

3. A device of the class described comprising a rectangular frame composed of a lower side bar to rest on the sill of a window frame, an upper side bar constituting an elevated sill to support the lower window sash

in raised position, and two vertical end bars secured to said side bars and adapted for snug reception between the usual guides of said lower sash, a continuous bead extending 5 around and integrally connected with the inner surfaces of the frame, said bead being spaced inwardly from the inner side of the frame, a door hinged to said inner side of the frame to swing into same against said 10 bead, a box projecting from the outer side

of the frame and comprising top, bottom, side and outer end walls, and an open inner end adapted to be removably inserted in the outer portion of said frame and means secured to the inserted inner ends of the side 15 walls of the box to removably secure the same in the frame.

In testimony whereof I have hereunto affixed my signature.

JAMES LOSE.
